United States Patent Office.

HENRY W. WILSON, OF BOSTON, MASSACHUSETTS.

Letters Patent No. 86,614, dated February 2, 1869.

IMPROVED DUMPING-SCOW.

The Schedule referred to in these Letters Patent and making part of the same.

To all whom it may concern:

Be it known that I, HENRY W. WILSON, of Boston, in the county of Suffolk, and State of Massachusetts, have invented a new and useful Improvement in Dumping-Scows; and I do hereby declare that the following, taken in connection with the drawings which accompany and form part of this specification, is a description of my invention sufficient to enable those skilled in the art to practise it.

Dumping-scows have for some years been made substantially as large flat-boats, decked over at their sides and ends, so as to make a water-tight chamber or chambers, of sufficient capacity or displacement to sustain the load proposed, this being carried in a flaring or hopper-like receptacle, made in the middle of the scow, which receptacle has an opening entirely through the scow, which is provided with drops or flaps, which open downward and outward, the flaps being double, closing along the longitudinal centre of the scow, and being hinged at each side of the opening.

These falls or flaps are held in place, so as to sustain the load, by means of chains passing from them over a windlass arranged over the fore-and-aft centre of the scow, so that, when the windlass is turned in one direction, the chains secured to the flaps slacken, and the falls gravitate downward, and upon turning the windlass in the other direction, the flaps are raised and closed thereby.

Now, these scows cannot be used for filling upon flats up to their loaded draught of water, for the reason that the flaps are so hung thereon, that, to open them to discharge the load, there must be a considerable depth of water below the bottom of the scow, so that the flaps may, in falling, project a considerable distance below the bottom of the scow, usually, in practice, about twenty inches, so that, unless the depth of water below the bottom of the scow, when loaded, is about the distance to which the edges of the flaps project when open, the load, not finding a free outlet, wedges and jams in escaping, and thus prevents discharge of the load, except where the water is deep enough to allow the flaps to assume a nearly vertical position.

My invention consists in so hinging or hanging the flaps of dumping-scows, that they will not project sufficiently below the bottom thereof to cause, by their striking on the ground beneath, such a contraction of

the dumping-opening as will prevent the discharge of the load.

In the practice of my invention, I prefer to have the edges of the flaps come flush with or within the bottom of the scow; but a small projection beyond it, such as will not cause the flaps to retain the load, by insufficient opening, while not advisable, will be no departure from the gist of my invention.

The drawing illustrates, in cross-section, an embodiment of my invention.

a is the bottom of the scow.

b b, the outer sides.

c, the deck.

e e, the inner sides, forming the well through the scow, while the hopper, which is bounded by *f f f*, is partly elevated above the deck.

Communication between the hopper and the well is controlled by the flaps *g g*. These are hinged and hung, as shown in the section, the flaps being shown in black lines, as open or down, and as closed or up, in red lines.

The fore-and-aft windlass is marked *h*, and the chain from the flaps to the windlass is denoted by *i*.

It will now be obvious that wherever a loaded scow of this modified construction can be floated, there it can discharge, and float off free from its cargo, for the hopper discharges into the well, the flaps opening wide to prevent jamming or choking, and when the load is discharging, and no longer wholly rests on the scow, this rises by its buoyancy, so that it rises from the matter discharged.

This rising of the scow begins the moment the load moves down in the hopper, and the form which the deposit takes by gravitation is not unlike the reverse of the interior of the hopper.

I claim a floating scow, having a mud-chamber, with inclined sides, and supported on the air-chambers, and having its long narrow flaps, which make the bottom-outlet of the mud-chamber, so arranged that when they are let fall by the windlass, they do not project beyond the scow-bottom, substantially as and for the purpose specified.

HENRY W. WILSON.
